UNITED STATES PATENT OFFICE.

MAGNUS N. SILVER, OF BERGLAND, ONTARIO, CANADA.

TOOL-HANDLE.

1,366,030.

Specification of Letters Patent. Patented Jan. 18, 1921.

Application filed May 3, 1917. Serial No. 166,165.

To all whom it may concern:

Be it known that I, MAGNUS N. SILVER, a citizen of Sweden, residing at Bergland, in the Province of Ontario and Dominion of Canada, have invented certain new and useful Improvements in Tool-Handles, of which the following is a specification.

This invention relates to improvements in tool handles and its object is to provide a handle which will positively retain the tool in operative position regardless of the use to which it may be subjected. A further object is to provide a handle that will hold the tool fast in hot, cold, wet or dry weather and regardless of the contraction or expansion of the handle helve. With the foregoing and other objects in view the invention consists in the combination and arrangement of parts to be hereinafter fully described in this specification, pointed out in the appended claim and illustrated in the accompanying drawing which forms a part of the specification and in which—

Figure 1 is a side elevation, partly in section, of my tool handle illustrating its application.

Fig. 2 is an inverted perspective view of the wedge member employed.

Fig. 3 is a top plan view of Fig. 1.

Like reference characters denote corresponding parts throughout.

The reference numeral 1 denotes the tool, in this case an ax, to which my improved handle may be applied. The handle comprises the helve 2 formed with a central vertical socket 3 adapted to receive the retaining screw 4 which passes through an opening 5 formed in the oval shaped retaining plate 6 which plate is formed along the

edge of its under side with the cuneiform beads 7, 8 which are spaced apart and which are of the general shape of the end of the helve 2 and designed to encompass the same and so wedge in between the helve and the tool 1 as best shown in Fig. 1.

When the helve is driven through the opening in the tool in the usual manner the retaining plate is applied. The beads 7, 8 are driven between the tool and helve and the plate retained in position by the screw 4. Expansion of the helve will only make a closer fit of the same with the tool; contraction of the helve is taken care of by forcing the screw 4 further into the helve and so driving the beads 7, 8 into the space formed between the tool and helve and tightening said members.

What is claimed is:—

In a tool handle, a helve formed with a central longitudinal socket, an oval apertured retaining plate of greater breadth than the end of said helve and adapted for overlapping disposition thereupon, cuneiform beads formed marginally of said retaining plate, said beads being spaced apart with their open ends adjacent each other, said beads being designed to encompass said helve and to wedge in between the same and the tool, and a screw adapted for insertion in the apertured portion of said retaining plate and into the socket of said helve.

In testimony that I claim the foregoing as my own I have hereto affixed my signature in the presence of two subscribing witnesses.

MAGNUS N. SILVER.
